(57) **CLAIM**

The ornamental design for an operator cab for construction equipment, as shown and described.

DESCRIPTION

FIG. 1 is a perspective view of an operator cab for construction equipment showing my new design.

FIG. 2 is a front view thereof.

FIG. 3 is a rear view thereof.

FIG. 4 is a right side view thereof.

FIG. 5 is a left side view thereof; and,

FIG. 6 is a top view thereof.
